HOMER ADDAMS, OF OSWEGO, NEW YORK

HEATING BOILER

Application filed November 19, 1927. Serial No. 234,321.

This invention relates to boilers in general and more especially to boilers fired with fuel such as powdered coal, oil and gas under pressure.

5 With boilers utilizing fuel such as powdered coal, oil and gas under pressure, as compared to ordinary coal fired boilers, considerable difficulty has been encountered when attempting to provide a fire-box spacious enough to approach perfect combustion. If the fire-box or furnace were too small, imperfect combustion would result. If the fire-box approached the size necessary to accommodate a space at all commensurate 10 with the space necessary for perfect combustion, the necessarily large space so required with the expedients heretofore practiced, made such fired boilers objectionable especially for use in buildings where space was 15 scarce, unobtainable or very valuable.

The present invention aims to provide a fire-box or furnace whereby fuel such as powdered coal, oil and gas under pressure can with facility be used and a minimum space 20 required for the fire-box or furnace commensurate with perfect combustion.

To this end, the present invention aims to provide a fire-box or furnace which will cooperate with the burner or discharge nozzle 25 of the fuel such as powdered coal, oil and gas under pressure to cause the fuel and resultant flame to move at a great velocity in a gyratory path of movement, whereby the fuel and flame will remain in the fire-box or furnace 30 a considerably longer time than as compared to fuel which is passing through the fire-box or furnace in straight lines, and thus permit the formation of a smaller fire-box or furnace with a given result as compared to a 35 fire-box or furnace where the fuel and flame pass in straight line paths of movement. From the foregoing it will be seen that it is not an aim of the invention merely to delay 40 the passage of the fuel and flame out of the fire-box or furnace but to facilitate the rapid 45 passage of the fuel and flame through an extended path of movement in a fire-box or furnace of a given area to facilitate the thorough combustion of the fuel before the flame 50 passes into the flue pipes.

Specifically, the present invention aims to provide a fire-box or furnace having a vertically extending cylindrical wall cooperating with a burner or fuel discharge nozzle to cause the fuel and resulting flame to move 55 through gyratory paths of movement at a great velocity before discharging into the flue pipes.

Specifically, the invention further contemplates the provision of a fire-box or furnace 60 having a lower vertically extending cylindrical chamber, an upper restricted discharge passage to the flue pipes, and a burner or fuel discharge nozzle for powdered coal, oil or gas entering the lower cylindrical chamber 65 whereby the restricted passage will cooperate with the cylindrical chamber and the velocity of the fuel being received to cause the fuel and resulting flame while passing through the lower cylindrical chamber to pass 70 through gyratory paths of movement at great velocity before discharging into the flue pipes from the upper restricted passage.

It is a still further object of the present invention to provide a lower vertically extending cylindrical chamber, an upper restricted discharge passage to the flue pipes, and a burner or fuel discharge nozzle positioned in the center of the base of the lower cylindrical chamber, which burner is constructed to impart a rotary movement to the fuel as it leaves the burner, such as a rotary burner or the like, whereby the fuel under pressure discharging from the burner in a rotary direction will cooperate with the vertically extending cylindrical wall of the lower cylindrical chamber to cause the fuel and resulting flame to pass through gyrating paths of movement at great velocity before discharging into the flue pipes from said restricted passage.

It is a still further object of the present invention to provide a boiler having an extended cylindrical water jacket surrounding the fire-box or furnace, which water jacket is in communication with the water in the main section of the boiler surrounding the flue pipes, whereby the maximum of heating surface for the boiler is provided for a given space and area of boiler.

These and other features, capabilities and

advantages of the present invention will appear from the subjoined detailed description of specific embodiments thereof, illustrated in the accompanying drawings, in which—

5 Figure 1 is a longitudinal section of a boiler having a rotatable burner located in the center of the base of the fire-box or furnace;

Fig. 2 is a section on the line 2—2 of Fig. 1.

In the embodiment illustrated in Fig. 1, there is illustrated a vertically extending cylindrical portion A supported on a base B, and a horizontally extending cylindrical portion C extending rearwardly from the portion A and supported by the standard 10 1 at its rear end. The rear end of the portion C is provided with a chimney extension 2. The fire-box or furnace is formed in the portion A by means of the lower cylindrical inner wall 3 secured to the base B, the front wall of which extends up to a point just below the water level 4 and continues rearwardly by means of the arc-shaped portion 5 to the rearward downwardly extending portion 6 connecting with the horizontally extending portion 7 just 15 about at the lower level of the portion C to communicate with the downwardly extending portion 8 of the cylindrical wall 3 adjacent to and concentric with but separated 20 from the outer shell 9. The outer shell 9 extends into the shell 10 of the portion C, the outer shell 9 forming the outer cylindrical shell of the portion A, and is spaced from the inner shell of the fire-box or furnace to 25 form a water jacket around the lower cylindrical portion L of the fire-box or furnace and around the upper restricted portion U of the fire-box. The section 6 of the upper 30 restricted portion U is connected to the tube sheet 11 between the chimney 2 and the portion C by means of the flue pipes 12 in the usual way.

From the foregoing it will thus be seen that the lower portion of the wall 3 spaced 35 from the outer wall 9 of the vertically extending portion A, forms with the second wall, composed of the offset portions 6 and 7 and the upper portion of the wall 3, an extended radiant heat exchanging furnace 40 surface.

As illustrated, the inner shell of the lower portion L is considerably extended as compared to the usual fire-box of this type heretofore in use, and forms with the remaining 45 inner shell of the fire-box substantially twenty per cent of the heating surface or heat exchanging surface of the boiler as compared to approximately ten per cent of the heating surface or heat exchanging surface 50 of a boiler used in the practice with ordinary coal fired boilers, thus doubling the high temperature surface of the boiler which is exposed to radiant heat.

Furthermore, the elongated skirt or vertically extending cylindrical water jacket 55

formed by the walls 8 and 9 for the fire-box chamber L serves to reduce the heat loss to a minimum, the water in such extended skirt forming a part of the main water supply to be heated taking up the heat, whereby the heat transmitted to the walls of the fire chamber will be used to heat the water to be heated and thus prevent loss of the same. By means of this water jacket, furthermore, leakage of the furnace structure may be ignored since there will of course be no interconnected sections for the fire-box wall and consequently no joints between such sections to be maintained.

The fuel discharging into the fire-box chamber L is preferably initially deflected or given an initial rotary movement to be continued when engaging the cylindrical wall 8, and thereby intensified. For this purpose there is preferably provided a burner or fuel discharge nozzle which causes a rotary movement to be imparted to the fuel as it leaves the burner. To this end, there is illustrated in the present instance, a rotatable burner or fuel discharge nozzle 14 which is located 60 in the center of the base partition 13 between the supporting base B and the fire-box L, which is connected by a conduit 15 to a suitable supply of fuel such as powdered coal, oil or gas and the air pressure in the usual way.

As the fuel under pressure is discharged into the lower chamber L in a rotary direction, as indicated by the arrows 16, it cooperates with the inner cylindrical wall 3 65 to continue in a gyratory cyclonic action, as indicated by the arrows 17, to pass in an upwardly moving cyclonic direction, that is, through an upwardly extending cyclonic 70 passage of movement into the restricted chamber U where its whirling action is continued until it enters and discharges through the tube sheet 6 into the flue pipes 12. Due to the vertically extending cylindrical form of the lower chamber L and the upward 75 draft through the chamber U, the speed or velocity of the fuel and resulting flame as it leaves the nozzle is increased so that while momentarily delayed in the lower chamber L, the fuel and flame is moving at a tremendous 80 velocity in a cyclonic path on its way to the restricted passage U. While the fuel and resulting flame pass through this cyclonic spiral action, it of course is constantly being subjected to a violent turbulent agitation due to the constant expansions that are taking place in the moving masses as 85 combustion proceeds.

It is furthermore to be noted that the conductive heat exchanging furnace surfaces defined by the flue pipes are arranged to co-operate with horizontally extending flowages of heat transferring gases, while the radiant heat exchanging furnace surfaces defined by the walls of the firebox portions L and U 90

are arranged to cooperate with gases and products of combustion that are moving in cyclonic circuitous paths of movement that spiral upwardly from the fuel inlet to discharge from the restricted portion U into the flue pipes 12. From this it will be seen that the radiant heat exchanging surfaces are exclusively composed of flowage deflecting walls, whereby the intensely hot gases generated in the fire-box portions are constantly caused to slip along the walls of the fire-box portions. In this way, extended radiant heat exchanging furnace surfaces are provided, and at the same time, due to this slippage producing arrangement, such surfaces are in no danger of injury from straight line flames, and furthermore a minimum fire-box area or space provided to afford a maximum movement of the fuel and resulting flame, so necessary to effect perfect combustion.

It is obvious that various changes and modifications may be made to the details of construction without departing from the general spirit of the invention as set forth in the appended claim.

I claim:

In a boiler, the combination of a vertical combustion chamber cylindrical throughout the major portion of its height and terminating in an extension of restricted cross-sectional area offset from one side of the longitudinal axis of said major cylindrical portion, a vertical shell spaced from the combustion chamber and surrounding the same to provide a water chamber, a horizontal shell intersecting the vertical outer shell in the plane of the offset part and on the side of said outer vertical shell opposite said offset part, the inner vertical wall of said offset portion constituting a flue sheet, smoke tubes connected to said flue sheet and extending longitudinally of said horizontal shell to communicate with an outlet for the gases, and a mechanical rotatable burner positioned centrally of the base of said combustion chamber to discharge its fuel upwards in a spiral path.
